METHOD AND APPARATUS FOR SHIPPING ENGINES

Application filed April 11, 1927. Serial No. 182,557.

This invention relates to loading and unloading methods and apparatus and refers more particularly to an improved method and apparatus for shipping engines such as internal combustion engines.

Heretofore it has been customary in shipping engines in freight cars and other conveyances to construct individual crates ordinarily made of wood, for each engine. This practice involves considerable expense in lumber cost as well as in labor in constructing the crates, placing the engines in the crates and generally handling the crates both at the shipping end and at the receiving end or destination. Aside from the cost of the lumber many of the crates are broken and otherwise damaged by general depreciation. A further expense and difficulty under the practice heretofore resides in checking up the crates shipped. Frequently the crates are not returned to the shipper and a check up must be made to determine such a situation. The crates frequently are damaged in removing the engines and the period of usefulness of a crate is relatively short, i. e. only a relatively few number of shipments, the consignee often being charged for lost and damaged crates. Hence under the past practice of shipping engines considerable expense is incurred both to the consignor and consignee.

Our invention provides a novel method and apparatus for eliminating the individual crates for the engines and generally materially reduces the labor and material costs involved both to the consignor and consignee.

Our invention further has for its object the provision of a simply constructed and conveniently operable apparatus for handling the engines in loading and unloading for and from shipment respectively.

A further feature of our invention resides in providing novel means for securely locating the engines in place in a freight car or other conveyance whereby the engines may be closely nested and securely fixed against accidental displacement during shipment, and yet may be quickly and conveniently removed from the freight car at the destination. One advantage resulting from this feature of our invention resides in the ability to so close-

ly nest the engines that the established minimum load per car may be obtained without decking the motors. Heretofore, in order to receive the full benefit of the shipping cost per car it was often necessary to deck the crated engines since the crates took up a relatively great amount of the available floor space of the freight car.

With the above and other objects in view our invention further resides in the novel combination and arrangement of parts more particularly hereinafter described.

Referring to the accompanying drawings in which like reference characters indicate corresponding parts,

Fig. 1 is a perspective view of the interior of a freight car illustrating one manner of shipping engines according to our invention.

Fig. 2 is a like view at right angles to Fig. 1,

Fig. 3 is a transverse section of the freight car showing the loading and unloading apparatus,

Fig. 4 is a detail sectional view along 4-4 of Fig. 3,

Fig. 5 is a detail sectional view along 5-5 of Fig. 3,

Fig. 6 is a diagrammatic view illustrating one manner of supplying the motors from the production line to the loading apparatus,

Fig. 7 is a view corresponding to Fig. 1, illustrating a modified form of our invention, and

Fig. 8 is a view of the modification corresponding with Fig. 2.

In the drawings reference character A represents a typical freight car, such as ordinarily used for shipping engines and other articles, 10 representing the floor, 11 the end walls, 12 the side walls, and 13 the doors and door openings.

In carrying out our invention we have illustrated in Fig. 6 a system for conveying the engines B from the source of supply such as the manufacturing plant along the endless conveyor 14 which might run along the loading and unloading platform 15, then return to the plant. The conveyor 14 will ordinarily travel relatively slowly so that the engines 100

may be removed from the conveyor as they travel along the platform for loading in the freight cars.

One feature of our invention resides in providing a quickly attachable and detachable apparatus for loading and unloading the engines. To this end when it is desired to load a car, supporting brackets 16 are secured to the side walls 12 of the car by headed fasteners 17. The fasteners 17 may engage openings 18 in the brackets 16, these openings having connecting slots 19, the openings being of greater diameter than the heads of the fasteners 17 and the slots 19 being of lesser width whereby upon removal of the apparatus the fasteners may be left in place and the brackets removed by slightly raising them to register the fastener heads with openings 18 as will be readily understood. The brackets 16 are located well toward the top of the car and are provided with slots 20 for receiving the angle beams 21. The beams 21 have their opposite ends supported by brackets 16, these beams extending transversely across the car at suitable intervals along the length thereof. The beams 21 form a support for the spaced rails 22 and for convenience of quick assembly and disassembly the rails 22 are provided with supporting hooks 23^a which pass over the upper portion of beams 21. The rails 22 are thus removably located, spaced, and extended longitudinally along the car to form a track for the travelling rail or track 23, the latter being provided with supporting and guiding rollers 24^a engageable with the track 22. The track 23 carries the hoist 24, rollers 25 operating on the track 23. The hoist 24 may be either powered with a motor or may be manually operated so as to raise and lower the engines by engagement with hook 26. With the apparatus as thus far described it is apparent that we have provided a quickly assembled or disassembled apparatus for loading or unloading engines to or from any point in the car, the travelling track 23, carrying hoist 24 travelling longitudinally of the car and the hoist 24 travelling longitudinally of track 23 or transversely of the car.

In order to provide for passage of hoist 24 in and out of the car we have provided a loading and unloading track section 27 hinged at 28 so that when the car is moved the section 27 may be swung away from the door opening 13 to the dotted line position indicated at the left of Fig. 6. In loading an engine it is desirable to accurately and quickly align the tracks 27 and 23 and to this end a sliding key 39 is provided. This key may be moved across the end 30 of the track 23 whenever the hoist 24 is passed between tracks 23 and 27.

The loading track section 27 is provided with a portion 31 beyond the hinge 28, preferably curved to provide an end portion 32 terminating closely adjacent the conveyor 14

and facilitating removal of the engine from the conveyor. If desired the end 32 may be provided with a suitable switch to the conveyor 14 but we find it convenient in loading an engine to run the hoist 24 out to the point 32 and to engage hook 26 with the engine carried by conveyor 14, lifting or disengaging the engine from the conveyor hook or other carrying means. The hoist with the engine to be loaded is then passed along tracks 31, 27, and 23. The key 29 is then slid beyond the end 30, the travelling rail 23 then being free to move longitudinally of the car and the hoist transversely of the car to deposit the engine on the car floor. The track 23 is then returned to align with the section 27 and the key 29 again moved across the end 30 to permit the hoist 24 to travel to the end track 32 to pick up the next engine for the car being loaded from the conveyor 14.

In Fig. 6 we have diagrammatically illustrated one system of loading a plurality of engines into their proper cars. Thus conveyor 14 may carry all the engines, three types being shown at B, B', and B² for example, respectively for loading into and shipment by the freight cars A, A', and A². Each of these cars may be equipped with our loading apparatus as described above.

A further feature of our invention resides in the manner of nesting, locating, and securing the engines in position within the cars. Referring to Figs. 1 and 2 the engines are placed in position by our loading apparatus, upon spaced supports 33, preferably of wood extending transversely across the floor of the car, the ends of the supports 33 being properly spaced according to the longitudinal dimension of the engine by the spacers 34 secured as by nails to the supports 33. In order to prevent displacement of the supporting units formed by the members 33 and 34, unit spacers 35 may be provided. To further securely fix the engines in position end boards 36 may be placed at the ends of each transverse row of engines across the supports 33 and adjacent the end engines of each row. As shown in Fig. 1 engine spacing blocks 37 may be located between adjacent engines of each row, these blocks for convenience being located below upper positioning boards 38 overlying each row of engines. We next tie the engines of each row together by passing a tie member, wire, or metal strip 39 preferably entirely around the engines of each row, fixing the ends of the tie member in any convenient manner. Next, other ties 40 are passed preferably at several points along the length of each row of engines taking up any slack in the tie member 39 and serving to further secure the engines in position. It is generally desirable to pass the ties 40 beneath the supports 33 and above the boards 38, these ties for convenience being placed on the floor of the car before plac-

ing the supports 33. In this manner the engine supports 33 may be quickly placed in position, the engines then being positioned by the loading apparatus, followed by placement of the boards 38 and the ties. If desired the boards 33 may have their upper faces grooved to receive the engines, the grooves corresponding in general with the lower shape of the engine.

Instead of positioning the unit rows of engines transversely of the car, these rows might also be formed longitudinally of the car as shown in Figs. 7 and 8. In these views the supports 33' and upper boards 38' extend longitudinally of the car, ties 39' and 40' being employed substantially as described above with reference to Figs. 1 and 2. In Fig. 7 we have shown the ties 39' extending the length of the car, passing around the engines of each row respectively.

In unloading the cars the ties and upper boards are removed, the apparatus shown in Fig. 3 being employed to remove the engines from the cars. If desired the loading and unloading apparatus may be left in the car during shipment or may be built permanently in the car.

In testimony whereof, we affix our signatures.

G. L. LUNDBORG.
R. B. ISRAEL.

95

Our invention provides means for more quickly loading and unloading the engines, and for securely fixing the engines in position without the use of individual crates used heretofore. Furthermore a saving is made possible in the elimination of much of the lumber used heretofore in crates as well as crate losses and deterioration expenses.

With our invention the engines may be closely nested, making it possible to obtain the minimum required load in a freight car without the necessity of decking the engine.

40 We do not limit ourselves to the particular apparatus and arrangement of engine location as shown and described as it is apparent that many changes may be resorted to and still utilize the benefits of our invention. We

45 believe our invention to be of a very broad scope since we are aware of no method or apparatus making it possible heretofore to ship motors without the use of the individual crates.

50 What we claim as our invention is:—

1. The method of shipping internal combustion engines in freight cars consisting in installing a removable engine, conveying apparatus within the freight car, loading the

55 engines in the car by means of the apparatus, and tying the engines together in groups.

2. The method of shipping internal combustion engines in freight cars consisting in loading the engines in the car in groups and

60 connecting and tying the engines of each group together whereby relative movement is prevented.

3. The method of shipping internal combustion engines consisting in progressively feeding the engines toward a freight car,

65

loading the engines in the car in groups, and tying the engines of each group together so as to prevent their relative displacement during shipment.

4. Apparatus of the character described comprising in combination with a freight car, an engine hoist, means mounting said hoist within the freight car to permit said hoist to travel longitudinally and transversely of

70 and within the car, said means including a travelling track for the hoist, a pivotal track member movable into a position of alignment with the said travelling track, and a slidable key connecting the adjacent ends of the travelling track and the pivotal track.

5. The method of loading internal combustion engines into a freight car for shipment consisting in installing a knockdown engine conveying apparatus within the freight car, loading said engines with said apparatus, and removing the apparatus after the loading operation is completed and prior to shipment of the freight car.
